CLAIM

The ornamental design for a cargo pallet, as shown and described.

DESCRIPTION

FIG. 1 is a front perspective view of a cargo pallet showing my new design;

FIG. 2 is a top view thereof;

FIG. 3 is a front view, the rear being identical thereof;

FIG. 4 is a right side view, with the left side being identical;

FIG. 5 is a bottom view thereof;

FIG. 6 is a detailed view of a corner of the cargo pallet thereof; and,

FIG. 7 is a cross-sectional view thereof taken from lines 7—7 in FIG. 2 showing an extrusion profile.

The broken line showing of tie-down rings is included for the purpose of illustrating environment and forms no part of the claimed design.
